UNITED STATES PATENT OFFICE.

ALEXANDER C. LESLIE, OF HALLETTSVILLE, TEXAS, ASSIGNOR OF ONE-HALF TO
EDWARD GUTHRIE, OF HALLETTSVILLE, TEXAS.

STOVEPIPE-SUPPORT.

1,191,802.

Specification of Letters Patent. Patented July 18, 1916.

Application filed September 14, 1915. Serial No. 50,680.

To all whom it may concern:

Be it known that I, ALEXANDER C. LESLIE, a citizen of the United States, residing at Hallettsville, in the county of Lavaca and 5 State of Texas, have invented certain new and useful Improvements in Stovepipe-Supports; and I do hereby declare the following to be a full, clear, and exact description of the invention, such as will enable others 10 skilled in the art to which it appertains to make and use the same.

This invention relates to new and useful improvements in stove pipe supports, and the principal object of the invention is to 15 provide a novel means for holding a stove pipe in an upright position and preventing the same from becoming accidentally disarranged.

Another object of the invention is to provide a means for attaching the stove pipe rigidly to the stove to avoid danger of 20 loosening the pipe and permitting the scot to fall from the interior thereof about the room in which the stove is used.

25 A further object of the invention is to provide a device consisting of a base provided with a plurality of standards at spaced intervals around the stove pipe, reinforcing wires extending between the standards and 30 securing means at the upper ends of the standards to attach the same to the ceiling or roof of the building in which the device is used.

With these and other objects in view, the 35 invention consists in the novel combination and arrangement of parts which will be fully set forth in the following specification and accompanying drawings, in which:—

Figure 1 is a view illustrating my improved stove pipe support in use, and Fig. 2 40 is a fragmentary perspective view of the lower part of the support.

Referring to the drawings by characters of reference, the numeral 1 designates a 45 portion of a stove of the usual construction, while the numeral 2 designates the ceiling of the building through which the stove pipe extends.

3 designates the top of the stove provided 50 with the usual downturned flange, and the numeral 4 designates as an entirety the stove pipe support. This stove pipe support above referred to, designated generally by the numeral 4, comprises the base member

5 formed of a strip of material, the central 55 portion 6 of which is provided with parallel sides forming a substantially square portion surrounding the stove pipe. A central opening 7 is formed in the portion 6, and the opposite ends of the base member 5 60 taper and are provided with the downturned flanges 8, which in turn are formed at the lower extremities with the inwardly and upwardly extending flanges 9. The flanges 8 conform to the shape of the outer side of 65 the downturned flange on the top of the stove 1, and the flange 9 forms a hook for engaging the under side of the flange on the top of the stove to hold the base member 5 in place. The central aperture 7 receives 70 the stove pipe, designated by the numeral 10, as clearly shown in the drawings. A plurality of apertures 7' are formed around the central opening 7, and secured within these apertures in any suitable manner are 75 the rods 11, which extend upwardly in parallel relation and are secured at their upper ends to suitable eyes 12, which are secured in the ceiling 2. The upper ends of the rods pass through the eyes and are bent 80 over to form loops, so that the said rods will remain in vertical position, as shown.

In order to reinforce the rods throughout their length, they are provided at spaced intervals with the wires 13, which are joined 85 to the rods at 14, preferably by welding, but it is to be understood that any other suitable method may be employed. The ends of the wires are lapped free and are designed to be intertwined, as at 15, to form 90 a rigid joint therebetween and thus enable the device to be used on stove pipes of various sizes.

It will be apparent from the foregoing that in use the device is assembled, as illustrated in the drawings, and will effectively 95 form a guard surrounding the stove pipe on all sides, and also form a support for said stove pipe in case the same may be struck. It will be apparent that the rods will protect the pipe, and prevent the same from 100 being struck by an object and becoming disjoined, thereby insuring the proper conducting of the hot gases from the stove.

While in the foregoing there has been 105 shown and described the preferred embodiment of this invention, it is to be understood that such changes may be made in the com-

bination and arrangement of parts as will fall within the spirit and scope of the appended claims.

What is claimed is:—

1. The combination with a stove, a stove pipe and ceiling of a building, of a stove pipe support comprising a base plate, flanges on the base plate to secure the device to the top of a stove, rods extending 10 upwardly from the base plate, and surrounding the stove pipe, means connecting the rods to the ceiling of the building, and wires connected to the rods and surrounding the pipe.
- 15 2. The combination with a stove, a stove pipe and ceiling of a building, of a base plate having a central opening formed therein, flanges formed at opposite ends of the plate for engaging the under edges of the top of

the stove, the opening in the base plate being 20 adapted to receive the stove pipe, the plate being also formed with a plurality of apertures disposed in spaced relation and around the central opening, rods secured in the last named apertures and extending upwardly 25 therefrom, means to secure the upper ends of the rods to the ceiling of the building, and wires welded to the rods and connecting the same to hold them in parallel relation, said wires surrounding the stove pipe 30 and the ends of the wires being intertwined.

In testimony whereof I affix my signature in presence of two witnesses.

ALEX. C. LESLIE.
